NOISE SUPPRESSION CIRCUITS

Joseph A. Worcester, Jr., Fairfield, Conn., assignor to General Electric Company, a corporation of New York

Application July 22, 1942, Serial No. 451,847

18 Claims. (Cl. 250—20)

My invention relates to noise suppression circuits, and it is particularly applicable to noise suppression circuits for automatically rendering the output circuits of a frequency modulation receiver inoperative when no signals are being received or when the level of a received signal is below a predetermined selectable value. More specifically, the present invention is an improvement upon the arrangement shown in my co pending application Serial No. 407,543, filed August 20, 1941, and assigned to the same assignee as the instant application.

It is well known that objectionable noises may be emitted by the signal reproducer of a radio receiver during those intervals when no signals are being received or while the receiver is being tuned between carrier channels. These noises may arise from a great many causes including cross-modulation effects, natural atmospheric static, locally produced high frequency electrical disturbances, "shot" effects, and thermal agitation of the tubes and circuits of the receiver itself, etc. Therefore, various "squelch" circuits have heretofore been proposed for muting the sound reproducer except when the receiver is tuned to a signal of sufficient strength to override the noise level and provide satisfactory reproduction. The operation of such circuits has variously been designated by such terms as "background noise suppression," "interchannel noise suppression," and "carrier-off noise suppression."

It is well known that a properly designed frequency modulation receiver inherently provides a high signal to noise ratio so long as the received signals exceed a predetermined level. This is due in large measure to the action of the amplitude limiting circuits which transmit the desired frequency modulation but discriminate against amplitude modulation. Thus so long as any signal sufficiently strong to operate the limiter is received, any noise voltages which cause undesired amplitude modulation of the signal are reduced to a very low level at the limiter output and do not cause objectionable disturbances in the sound reproducer. Accordingly, noise suppression or "squelch" circuits heretofore proposed have been based upon the principle that the sound reproducer should be muted until the signal voltages appear which are of themselves sufficiently strong substantially to saturate the limiter.

In certain applications, however, it has been found desirable to provide a certain degree of adjustability so that the cutoff point of the sound reproducer disabling means with respect to the strength of a received signal may be varied at will, thereby to permit the reception of weak signal voltages in spite of the fact that a certain amount of amplitude modulated noise voltage

is also reproduced. It is also desirable to provide means for substantially instantaneously disabling the noise suppression circuit as soon as a signal voltage of the selected strength appears.

Accordingly, it is a general object of my invention to provide a new and improved carrier-off noise suppression circuit which is particularly adapted to the requirements of a frequency modulation receiver.

It is a further object of my invention to provide a new and improved carrier-off noise suppression circuit which is operative automatically to squelch or mute the sound reproducer so long as the amplitude of the frequency modulated carrier wave is below any predetermined selectable value.

It is a still further object of my invention to provide a new and improved carrier-off noise suppression circuit which is automatically operative to disable the sound reproducer so long as the amplitude of a received frequency modulated carrier voltage remains below any predetermined selectable value.

My invention also has for its object a noise suppression circuit having means for rendering the circuit completely and substantially instantaneously inoperative upon the occurrence of a signal voltage of predetermined value.

It is another object of my invention to provide an improved carrier-off noise suppression circuit whose cutoff point with respect to the amplitude of a received frequency modulated carrier voltage is selectable and which is very sensitive in that its noise suppression effect disappears substantially instantaneously upon the attainment by the carrier of the preselected level.

In a preferred embodiment of my invention the noise voltages supplied to the limiter under no-signal or weak signal conditions are detected and utilized to provide bias potentials for reducing the transfer efficiency of a portion of the transmission channel following the limiter. Preferably one of the amplifying stages following the limiter is completely blocked and the sound reproducer thereby effectively muted. If the noise voltage indication is taken from the limiter output, such an arrangement in itself will provide automatic cutoff of the noise suppression effect as soon as a signal voltage of just sufficient magnitude to saturate the limiter is received, by reason of the fact that at this point amplitude modulation in the limiter output is prevented and the squelch voltage automatically collapses. It will be understood of course that noise voltages may also, if desired, be detected at the limiter input. In another modification this arrangement is used. Where such a system is used noise voltages are still detectable even though the limiter is saturated,

so that special means must be provided to disable the squelch circuit when a received signal voltage attains the desired magnitude.

For the purpose of providing selectable cutoff of the squelch voltage for any predetermined carrier signal strength, I combine in opposing relation with the detected noise bias voltage a bias voltage of controllable and substantially constant value to obtain a net or differential bias voltage of selectable value whereby by diminution of the noise bias voltage with increasing carrier voltage the net squelch voltage may be brought to zero at any predetermined selectable signal level. A sensitive trigger action of the squelch circuit is insured by providing means for insuring immediate collapse of the differential bias voltage as soon as it tends to reverse due to predominance of the constant controllable bias. When such a differential voltage is used the noise voltages may be taken either at the limiter input or output.

The features of my invention which I regard as novel and patentable are set forth with particularity in the appended claims. My invention itself, however, together with further objects and advantages thereof may best be understood by referring to the following detailed description taken in conjunction with the accompanying drawing in which Fig. 1 is a schematic representation, partly in the form of a conventionalized one-line diagram, of a frequency modulation receiver embodying my invention; and Fig. 2 schematically represents a modified form of my invention, some of the conventional portions of the frequency modulation receiver being omitted for simplicity. Fig. 1 has been utilized to illustrate two modifications of my invention by the interposition of a selector switch for choosing various circuit connections. In order to facilitate comparison of the two figures and to simplify the accompanying description, like reference numerals have been placed upon corresponding elements of the figures.

Before proceeding further with the description of the illustrated embodiments of my invention, I wish to explain the meaning of certain terms as used hereinafter in the specification and the appended claims.

I intend such terms as "noise" or "noise voltages," unless otherwise qualified, to include all undesired voltages which may accompany the desired signals or be modulated upon them, or which may exist in the absence of the desired signals. For example, these voltages may be caused by cross-modulation effects, adjacent channel interference or non-linearity of the transmission channel; they may be caused by thermal agitation effects, "shot" effects, and related phenomena which occur in the receiver itself and give rise to disturbances of the so-called continuous or "hash" type; or they may be caused by natural atmospheric static, ignition interference and the like which occur outside the receiver and give rise to disturbances of the so-called impulse type. Such voltages normally vary in intensity or amplitude at irregular and rapid rates.

By the term "amplitude modulation" and the like I intend to include all amplitude variations in the envelope of high frequency voltages appearing at specified points of the transmission channel, irrespective of the precise character of these voltages. Thus, for the purpose of my invention these voltages may constitute periodic signal voltages either unmodulated or modulated

in frequency or phase by desired signals, or irregular voltages such as are characteristic of the types of noise.

By the term "frequency modulation" I mean to include any form of modulation produced by varying the frequency or phase of the carrier wave as distinguished from modulation produced by varying the amplitude of such a wave.

In the diagrammatic representation of a frequency modulation receiver shown in Fig. 1, many of the elements may be conventional and their details of construction are not material to my invention. Therefore to simplify the drawing and the description of such elements, they have been shown merely in block form. The receiver illustrated provides a signal channel which is for the most part of the conventionalized superheterodyne type. Signals received at an antenna 18 are amplified in the usual radio frequency amplifiers 16 and combined in a mixer 12 with locally generated waves supplied from an oscillator 13. The carrier waves of the resulting intermediate frequency are then amplified in intermediate frequency amplifiers 14. In frequency modulation receivers of the usual design it is often the practice to pass the intermediate frequency waves through two amplitude limiters in cascade in order to secure better limiting action. Thus in the illustrated embodiment of the invention some of the amplitude modulation is removed in a first limiter 15, and practically all of the remaining amplitude modulation is removed in a second limiter 16.

The intermediate frequency carrier waves at the output of the second limiter 16 are of substantially constant amplitude and contain only the frequency modulation which is representative of the intelligence being transmitted. These waves are demodulated in a slope filter or discriminator 17. Various forms of apparatus suitable for this purpose are well known in the art. One type of frequency modulation detector circuit which I have found to be satisfactory is described in Patent No. 2,121,103, Seeley, granted June 21, 1938.

The demodulated audio signals are reproduced by supplying them first to an audio frequency amplifier 18, further amplifying them in an audio power amplifier 19, and then supplying them to a suitable signal translating device such as a loud-speaker 20.

The second limiter 16 comprises a pentode amplifier tube 30 having an input circuit including a coupling capacitor 31 and a grid resistor 32 connected between its control grid 33 and its cathode 34, and an output circuit including a tuned circuit 35 connected to its anode 36. Anode operating potentials are supplied in conventional manner from a suitable source of power, such as a battery 37, through the usual decoupling resistor 38. The screen grid 39 of the pentode tube 30 is similarly supplied with operating potentials from the common power supply source 37 through a decoupling resistor 40, and is coupled to the cathode 34 by means of the usual screen grid by-pass condenser 41. The output circuit of the limiter 16 is also provided with a by-pass condenser 42 of conventional form.

The operation of the limiter 16 will be readily understood by those skilled in the art without further detailed explanation. The limiter is self-biased by means of the capacitor 31 and the grid resistor 32. It is so adjusted as to draw anode current only between the limits at which positive

grid current flows and at which anode current cutoff takes place.

As previously explained, the diagram of Fig. 1 is a combined illustration of two modifications of my invention, there being provided a manually operable single pole, double throw selector switch 45 which, when in one position, makes proper connection for operation of the noise suppression circuit according to one modification of the invention, and when in the other position, connects the noise suppression circuit in accordance with a second modification. The form of the invention resulting from positioning the selector switch 45 in the manner illustrated in Fig. 1 will first be described.

In the circuit of Fig. 1 the time constant of the grid circuit 31, 32 is such that the pentode 30 functions essentially as a grid power detector for amplitude modulation components within the audio frequency band. Therefore it produces audio voltages across an audio frequency load in the anode circuit. Such a load is provided by the decoupling network comprising the resistor 38 and the capacitor 42. Accordingly, noise voltages at audio frequency appear at the point 50. These voltages are supplied through a low pass filter comprising a resistor 56 and a capacitor 57 and through a blocking condenser 55 to a diode rectifier 58. The low pass filter 56, 57 has for its purpose the removal of intermediate frequency, while the condenser 55 removes any direct current in the limiter output. Any detected audio frequency voltages which are thus applied to the diode detector 58 are rectified and appear across a load resistor 59 as unidirectional voltages having a magnitude proportional to the degree of amplitude modulation present in the noise voltages.

The unidirectional voltages appearing across the resistor 59 are filtered through a low pass filter comprising a resistor 60 and a capacitor 61 and impressed between a control grid 62 and the cathode 63 of a first audio amplifier tube 64 through a resistor 65. As indicated in the drawing, the voltages appearing across the load resistor 59 are of such polarity as to bias the grid 62 negatively with respect to the cathode 63 and, if the amplitude modulation present in the noise voltages at the output of the limiter 16 is sufficient, the bias voltages impressed upon the grid 62 are sufficient to reduce the amplification of the audio amplifier 64 to a very low level and preferably to bias it completely to cutoff, thereby reducing the transfer efficiency of or preventing transmission of signals to the sound reproducer comprising the power amplifier 19 and the loud-speaker 20.

I also provide a diode rectifier 70 connected across the terminals of the load resistor 59. Accordingly, when the noise voltages at the output of the limiter 16 are sufficient to bias the audio amplifier grid 62 negative with respect to its associated cathode 63, the plate 71 of the diode 70 is also biased negatively with respect to the cathode 72 of this tube and the diode 70 does not conduct and has no effect upon the operation. The function of the diode 70 will be described hereinafter.

As indicated earlier in this specification, it is preferable to provide such a high gain through the radio frequency and intermediate frequency amplifiers that the noise voltages impressed upon the limiter grid 33 develop self-bias potentials approaching values required to saturate the pentode tube 30 even under no-signal conditions. 75

Nevertheless, under such conditions it has been found that these voltages are not appreciably limited in amplitude in the limiter 16, and that substantial noise voltages are developed at the limiter output including modulation frequencies within the audio band.

As soon as a carrier signal is received which is sufficient to maintain the limiter 16 continuously saturated, the amplitude modulated audio noise voltages appearing at the point 50 almost completely disappear so that the bias voltage across the resistor 59 completely collapses. However, it has been found that the audio bias voltage developed across the resistor 59 under no-signal conditions is considerably more than sufficient to bias the audio amplifier tube 64 to cutoff. Consequently with the circuits thus far described it is necessary to receive carrier voltages of substantially full strength sufficient continuously to saturate the limiter 16 in order to reduce the negative bias of the grid 62 sufficiently to unblock the amplifier tube 64. This is due to the fact that considerable noise voltage amplitude modulation may still exist in the output of the limiter 16 even though a relatively weak signal voltage is being received.

Under certain circumstances such as in police emergency receivers, it is desirable to provide means for disabling the squelch circuits upon the reception of even a weak signal voltage, so that the weak signal may be reproduced if desired even though a certain degree of background noise is present. To provide for such a contingency, my invention includes means for selectively controlling the amount of cutoff bias supplied to the grid 62 of the amplifier tube 64. By suitably adjusting the net grid bias under no-signal conditions, I provide for complete collapse of this bias upon any predetermined degree of diminution of the noise voltage appearing across the resistor 59 occasioned by the reception of a weak signal voltage at the output of the limiter 16. To this end a substantially constant positive or opposing bias of selectable value is applied by means of an adjustable potentiometer 75 between the grid 62 and the cathode 63 of the amplifier tube 64 from the battery 31 through a resistor 76. The purpose of the resistor 76 is to reduce the positive bias to a suitable value, and the resistor is preferably so selected that the maximum negative noise bias under no-signal conditions exceeds the normal positive bias by an amount just sufficient to bias the tube 64 to cutoff. Thus, by way of example, if ten volts of negative bias are applied to the grid 62 by the rectified noise voltages under no-signal conditions, a positive bias of seven or eight volts may be applied from the potentiometer 75, so that the net bias of two or three volts negative is just sufficient to maintain the amplifier tube 64 inoperative. Under such conditions if a very weak signal voltage is received, thereby reducing the magnitude of the rectified noise voltage only slightly, the net negative bias applied to the grid 62 will be reduced sufficiently to render the amplifier tube 64 operative. Similarly, it will be evident that by decreasing the amount of positive bias from the resistor 75, the differential or net negative bias applied to the grid 62 may be increased, so that any desired necessary strength of signal voltage for rendering the amplifier tube 64 conductive may be selected.

The function of the diode rectifier 70 will now become apparent. It will be clear that, if the positive grid bias from the potentiometer 75 is so

adjusted that the net grid bias under no-signal or very weak signal conditions is just sufficient to bias the tube 64 to cutoff, a slight increase in carrier signal voltage will reduce the net grid bias on the tube 64 to zero. If, however, the received carrier wave should be of sufficient amplitude further to reduce the negative noise voltage, the net or differential bias upon the grid 62 would become positive due to the constant positive bias impressed through the potentiometer 75. In fact, if the carrier amplitude should be sufficient continuously to saturate the limiter 16, the negative noise voltage appearing across the resistor 58 would be reduced to zero and the full positive bias from the potentiometer 75 would be left upon the amplifier grid 62. The presence of the diode rectifier 70 precludes such a possibility in that, as soon as the net bias between the audio amplifier grid 62 and the audio amplifier cathode 68 goes positive, the plate 71 of the diode 70 will also assume a positive voltage with respect to the associated cathode 72, and the diode will conduct. Since the internal resistance of the diode 70 when conducting is very small compared with the magnitudes of the resistors 58 and 76, any positive bias which might otherwise be supplied to the grid 62 from the potentiometer 75 substantially vanishes.

Accordingly, it will now be evident that I have provided means whereby rectified noise voltages at the limiter stage may be differentially combined with an opposing bias voltage, thereby to adjust the maximum cutoff bias of a subsequent stage in the signal channel, such as an audio amplifier, to any desired value and thus select the carrier signal strength at which it is desired to have the cutoff bias of the amplifier stage disabled. My invention also provides means for insuring sensitive operation by maintaining the net amplifier grid voltage substantially at zero even though the rectified noise voltage itself goes to zero, thereby preventing reversal of the net or differential grid voltage.

The modified form of my invention represented at Fig. 1 with the selector switch transferred from the position shown in the drawing to the contact 88 differs from that described above only in certain particulars. According to this modification of the invention the source of positive potential from which a positive bias is applied to the grid 62 of the amplifier tube 64 through the potentiometer 75 is shown as a point in the limiter output circuit rather than the positive terminal of the battery 37. Specifically, the potentiometer 75 is connected to the plate return of the limiter 16 through a conductor 81 and a low pass filter comprising a resistor 82 and a condenser 83. This modification of the invention has the additional advantage that the positive potential of the plate 36 of the limiter 16, and therefore the positive potential applied to the control grid 62 of the audio amplifier 64, increases simultaneously with a decrease in the negative noise bias across the load resistor 58 of the squelch circuit. Thus, the net squelch bias on the amplifier tube 64 approaches zero more rapidly as soon as a weak carrier voltage is received, thereby further reducing the minimum carrier input necessary to disable the squelch circuit.

At Fig. 2, I have shown a modified form of my invention embodying certain refinements which have for their purpose an assurance that (a) the squelch circuit shall not cease to function in the presence of extraneous noise, either impulse or continuous, with a lack of signal or carrier volt-

age; (b) the squelch circuit shall not function in the presence of a predetermined minimum signal voltage; (c) the squelch circuit shall not be set in operation by the presence of a reasonable amount of amplitude modulation in the signal voltage. Briefly, these purposes are accomplished by receiving the noise indication from the grid of the first limiter and applying noise voltages thus received to the squelch circuit through a special squelch amplifier in combination with a high pass filter for removing low frequency components from the amplifier output.

Referring now more specifically to the diagram of Fig. 2, it will be noted that the circuit there shown is in many respects similar to that illustrated in Fig. 1, and to simplify the description and facilitate a ready understanding of the invention, corresponding elements of the system have been assigned like reference numerals. Voltages appearing at the control grid 33a of the first limiter 15 are utilized to set the squelch circuit in operation. The first limiter comprises a pentode tube 30a and a tuned output circuit 35a, the various elements of the pentode 30a being assigned reference numerals similar to those designating the corresponding elements of the pentode 30 of Fig. 1. Voltages appearing at the grid 33a may be either frequency modulated carrier signal voltages, amplitude modulated noise voltages, or both. As shown, the limiter grid voltage at 33a is applied to a control grid 90 of a squelch amplifier triode 91 through a voltage divider comprising a plurality of resistors 92, 93, and 94 connected in series circuit relation between the control grid 33a and ground. The resistors 93 and 94 are shunted by a capacitor 95, which, in combination with the resistor 92 and certain stray capacities present, serves as a low pass filter for removing voltages of intermediate frequency. Thus, only audio frequency voltages are applied to the grid 90 of the squelch amplifier 91. An audio frequency bypass condenser 93a shunts the resistor 93.

If now it is assumed that no carrier signal is present and that only amplitude modulated noise voltages are present at the limiter grid 33a, the audio frequency components of these voltages will be amplified by the squelch amplifier 91. The anode-cathode circuit of the amplifier 91 is supplied from a suitable source of direct current supply such as the battery 37. This output circuit also includes an iron core choke coil 97 which with the condenser 83 acts as a high pass filter to remove from the output of the amplifier tube 91 any low frequency components due to amplitude modulation of the audio frequency output of the squelch amplifier. In this manner amplified and detected audio frequency voltages are applied to the diode detector 58 and are rectified to develop across the load resistor 58 a negative bias potential of a magnitude proportional to the degree of amplitude modulation present in the noise voltages at the limiter grid 33a. The negative noise potential developed across the load resistor 58 is filtered in the low pass filter 80, 81 and supplied through the resistor 85 to the control grid 62 of the first audio amplifier tube 64 in the same manner as has been heretofore explained with reference to Fig. 1. However, due to the action of the squelch amplifier tube 91, the magnitude of the negative bias voltage thus applied to the grid 62 is considerably greater than that developed with a circuit arrangement similar to that of Fig. 1.

Accordingly, for the purpose of reducing the

cutoff potential applied to the grid 62 of the amplifier tube 64 and also for the purpose of providing an adjustable and sensitive or triggerlike operation as heretofore explained, the negative bias developed across the load resistor 59 is opposed by a positive bias of slightly less magnitude applied to the amplifier grid 62 from the supply source 37 through a variable squelch potentiometer 75, 75a. As heretofore explained, the positive bias is reduced to a suitable normal value by a resistor 76. The reverse potential short-circuiting diode 70 serves the same purpose as has been heretofore explained with reference to Fig. 1.

If now a signal voltage of substantially constant magnitude, but modulated with respect to frequency in accordance with the intelligence being transmitted, is applied to the grid 33a of the limiter 15 along with certain amplitude modulated noise voltages, the increased D. C. voltage applies an increased negative bias to the grid 90 of the squelch amplifier 91, thereby tending to cut off the amplifier. While the developed negative bias may not be sufficient to cut off the squelch amplifier 91, it will be sufficient to decrease the amplifier gain sufficiently so that the developed output voltage at audio frequency is reduced, thus reducing the negative bias across the load resistor 59 and the net negative bias on the grid 62 of the audio amplifier 64. It will of course be understood that, as in the modification of Fig. 1, the net negative bias on the grid 62 under no-signal conditions may be controlled by means of the potentiometer 75, 75a, thereby selectively to determine the minimum signal strength at which the squelch control opens or becomes ineffective. Also, the manner in which the diode 70 acts to preclude the imposition upon the control grid 62 of a net positive bias, thereby to insure rapid and permanent collapse of the net squelch bias at a selected cutoff point so long as the noise voltage remains reduced, has also been explained with reference to Fig. 1.

The circuit of Fig. 2 is so arranged that an increased negative bias applied to the control grid 90 of the squelch amplifier 91 without the presence of a signal voltage, as increased direct current bias due to increased extraneous noise, will not tend to unblock the first amplifier tube 64. For this purpose the voltage dividing resistors 93 and 94 are so selected that an increase in the negative bias applied to the squelch amplifier 91 by the application of increased noise voltages to the limiter is balanced by the increase in the audio noise voltage supplied through the bypass condenser 93a to the control grid 90 of the squelch amplifier 91. That is to say, the increased negative or cutoff bias applied to the grid 90 is counteracted by the greater audio frequency voltage applied to the grid, thereby to maintain the developed squelch bias across the load resistor 59 substantially constant in magnitude. It will be understood that increase in the negative bias on the grid 90 due to the presence of a signal voltage of substantially constant magnitude will provide the tendency to cut off the squelch amplifier 91, as previously described, but due to the fact that the audio frequency voltage is not thereby increased, it will not provide the counterbalancing tendency present with increasing noise voltages. Thus, there is neither a tendency to set the squelch circuit in operation in the presence of a frequency modulated signal voltage, nor a tendency to open the squelch with increased noise. Furthermore, the high pass

filter including the choke 97 precludes closing of the squelch due to modulation of otherwise ineffective audio voltages at the amplifier 91.

For completeness of illustration only and not in any sense by way of limitation, the following circuit constants are given as being typical for a frequency modulation receiver of the type represented at Fig. 2. These constants have been found to be satisfactory for the circuit elements of an emergency frequency modulation receiver adapted to receive signals in the vicinity of 30 to 42 megacycles and having an intermediate frequency channel tuned to about 4.55 megacycles. In this particular receiver the tube 30a was a type 7C7 pentode, the diode 58 and the squelch amplifier 91 were embodied in a single diode triode type 7C6, and the audio frequency amplifier 64 and the diode 70 were embodied in a second 7C6 type tube. Other circuit constants were as follows:

Capacitor 31a	mmf	50
Resistor 32a	ohms	270,000
Resistor 92	do	220,000
Resistor 93	do	470,000
Resistor 94	do	220,000
Capacitor 95	mmf	50
Capacitor 93a	mmf	470
Inductance 97	henrys	6
Capacitor 55	mmf	100
Resistor 59	megohms	1
Resistor 60	do	2.2
Resistor 76	do	2.7
Resistor 75	ohms	20,000
Resistor 75a	do	68,000
Capacitor 61	mfd	.1
Resistor 65	megohms	5.6

While I have shown certain preferred embodiments of my invention by way of illustration, it will of course be understood that I do not wish to be limited thereto since various modifications will occur to those skilled in the art. I therefore contemplate by the appended claims to cover any such modifications as fall within the true spirit and scope of my invention.

What I claim as new and desire to secure by Letters Patent of the United States, is:

1. In a radio receiving apparatus, a signal channel adapted to transmit a signal wave modulated in frequency within a band of frequencies in accordance with an impressed signal, said channel being also effective to transmit noise voltages appearing as audio frequency amplitude modulation of said signal wave, signal reproducing means coupled to said channel, means responsive to said amplitude modulation of said signal wave for at least partially disabling said signal reproducing means, means for rendering said disabling means substantially non-responsive to amplitude modulation of signal waves having a predetermined minimum amplitude, and means for controlling said disabling means to select said predetermined minimum amplitude.

2. In a radio receiving apparatus, a signal amplifier adapted to amplify a carrier wave modulated in frequency within a band of frequencies in accordance with an impressed signal, said amplifier being also effective to supply in its output substantial noise voltages modulated in amplitude at audio frequency, signal reproducing means coupled to said amplifier, means for developing a unidirectional potential proportional in value to the degree of amplitude modulation of waves supplied by said amplifier, means for reducing said potential in accordance with in-

65
60
70
75

crease in the level of carrier waves supplied by said amplifier, said potential being reduced substantially to zero when said waves attain a predetermined level, means for selecting said predetermined level comprising a second unidirectional potential of selectable value opposing said first potential thereby to provide a selectable and variable differential potential, and means controlled by said differential potential for at least partially disabling said signal reproducing means thereby to preclude the reproduction of noise voltages so long as said carrier wave is below said predetermined level.

3. In a radio receiving apparatus, a signal amplifier adapted to amplify a carrier wave modulated in frequency within a band of frequencies in accordance with an impressed signal, said amplifier being also effective to supply in its output substantial noise voltages modulated in amplitude at audio frequency, an amplitude limiter coupled to said amplifier, a signal reproducer coupled to said limiter, means associated with said limiter for developing a unidirectional potential proportional in value to the degree of amplitude modulation present in waves below a predetermined level supplied to said limiter, adjustable means for opposing said potential with a second unidirectional potential of selectable value thereby to provide a differential potential, and means controlled by said differential potential for at least partially disabling said signal reproducer, said adjustable means being operable selectively to render said disabling means ineffective in the presence of carrier waves at any level below said predetermined level.

4. In a radio receiving apparatus, a signal amplifier adapted to amplify a carrier wave modulated in frequency within a band of frequencies in accordance with an impressed signal, said amplifier being also effective to supply in its output substantial noise voltages modulated in amplitude at audio frequency, an amplitude limiter coupled to said amplifier, signal reproducing means including an electron discharge device having a control electrode coupled to the output of said limiter, means responsive to amplitude modulation of waves below a predetermined level supplied to said limiter to apply to said control electrode a bias potential proportional to said amplitude modulation, and adjustable means for applying to said control electrode an opposing bias potential of selectable value thereby to provide a differential bias potential of such polarity as to tend to disable said electron discharge device, said adjustable means being arranged to maintain said differential potential sufficient substantially to disable said electron discharge device in the absence of a carrier wave and selectively to reduce said differential potential to zero in the presence of carrier waves below said predetermined level.

5. In a radio receiving apparatus, a signal amplifier adapted to amplify a carrier wave modulated in frequency within a band of frequencies in accordance with an impressed signal, said amplifier being also effective to supply in its output substantial undesired noise voltages modulated in amplitude at audio frequency, an amplitude limiter coupled to said amplifier, said limiter being effective to remove amplitude modulation at carrier frequencies from the wave supplied to said limiter so long as a carrier wave exceeding a predetermined limiting level is supplied thereto, a signal reproducer including an electron discharge device having a control elec-

trode coupled to the output of said limiter, amplitude modulation detection means for developing a negative bias potential upon said control electrode proportional to amplitude modulation of waves supplied to said limiter below said limiting level, and means for supplying to said control electrode a positive bias potential of selectable value less than said negative potential so long as the amplitude of said carrier wave remains below a desired value thereby to supply to said control electrode a net negative bias potential sufficient substantially to disable said reproducing means until said carrier wave exceeds said desired value.

6. In a radio receiving apparatus, a signal amplifier adapted to amplify a carrier wave modulated in frequency within a band of frequencies in accordance with an impressed signal, said amplifier being also effective to supply in its output substantial noise voltages modulated in amplitude at audio frequency, an amplitude limiter coupled to said amplifier, signal reproducing means including an electron discharge device having a control electrode coupled to said limiter, means associated with said limiter for developing a unidirectional potential proportional in value to the degree of amplitude modulation present in waves below a predetermined level supplied to said limiter, adjustable means for opposing said potential with a second unidirectional potential of selectable value thereby to provide a differential potential, means for applying said differential potential to said control electrode to disable said electron discharge device, said adjustable means being operable selectively to render said disabling means ineffective in the presence of carrier waves below said predetermined level, and means for preventing reversal of said differential potential upon diminution of said first-mentioned unidirectional potential.

7. In a radio receiving apparatus, a signal amplifier adapted to amplify a carrier wave modulated in frequency within a band of frequencies in accordance with an impressed signal, said amplifier being also effective to supply in its output substantial noise voltages modulated in amplitude at audio frequency, an amplitude limiter coupled to said amplifier, signal reproducing means including an electron discharge device having a control electrode coupled to said limiter, means associated with said limiter for developing a negative bias potential proportional in value to the degree of amplitude modulation present in waves below a predetermined level supplied to said limiter, adjustable means for supplying a positive bias potential of selectable value to oppose said negative potential thereby to provide a differential bias potential, said adjustable means being operable selectively to reduce said differential potential to zero in the presence of carrier waves below said predetermined level, means for applying said differential bias potential to said control electrode to reduce the transfer efficiency of said electron discharge device, and means for preventing reversal of said differential potential comprising a second electron discharge device connected normally to be nonconductive and to become conductive upon any tendency of said differential potential to reverse.

8. In a radio receiving apparatus, a signal amplifier adapted to amplify a carrier wave modulated in frequency within a band of frequencies in accordance with an impressed signal, said amplifier being also effective to supply in its out-

put substantial noise voltages modulated in amplitude at audio frequency, an amplitude limiter coupled to said amplifier, signal reproducing means including an electron discharge device having a control electrode coupled to the output of said limiter, means responsive to amplitude modulation of waves below a predetermined level supplied to said limiter to apply to said control electrode a bias potential proportional to said amplitude modulation, adjustable means for applying to said control electrode an opposing bias potential of selectable substantially constant value thereby to provide a differential bias potential of such polarity as to tend to disable said electron discharge device, said adjustable means being arranged to maintain said differential potential sufficient substantially to disable said electron discharge device in the absence of a carrier wave and selectively to reduce said differential potential to zero in the presence of carrier waves below said predetermined level, and means associated with said electron discharge device for preventing a reversal of said differential bias potential.

9. In a radio receiving apparatus, a signal amplifier adapted to amplify a carrier wave modulated in frequency within a band of frequencies in accordance with an impressed signal, said amplifier being also effective to supply in its output substantial undesired noise voltages modulated in amplitude at audio frequency, an amplitude limiter coupled to said amplifier, said limiter comprising an electron discharge device having an output circuit and being effective to remove amplitude modulation at carrier frequencies from the wave supplied to said limiter so long as a carrier wave exceeding a predetermined limiting level is supplied thereto, a signal reproducer including a second electron discharge device having a control electrode coupled to the output of said limiter, amplitude modulation detection means for developing a negative bias potential upon said control electrode proportional to amplitude modulation of waves supplied to said limiter below said limiting level, means associated with said output circuit of said first electron discharge device for supplying to said control electrode a positive bias potential of selectable value less than said negative potential as long as the amplitude of said carrier wave remains below a desired value, and means responsive to a predominance of said positive bias potential to maintain the net potential upon said control electrode substantially at zero.

10. In a radio receiving apparatus, a signal amplifier adapted to amplify a carrier wave modulated in frequency within a band of frequencies in accordance with an impressed signal, said amplifier being also effective to supply in its output substantial noise voltages modulated in amplitude at audio frequency, an amplitude limiter coupled to said amplifier, said limiter comprising an electron discharge device having an output circuit, signal reproducing means including a second electron discharge device having a control electrode coupled to said output circuit, means responsive to amplitude modulation of waves appearing at the output of said limiter for applying to said control electrode a bias potential of proportional value, adjustable means for applying to said control electrode an opposing bias of selectable substantially constant value thereby to provide a differential bias potential of such polarity as to tend to disable said second

electron discharge device, the magnitude of said differential potential in the absence of a carrier wave being selectable by said adjustable means thereby to provide for reduction of said differential potential to zero in the presence of a carrier wave of desired amplitude.

11. In a radio receiving apparatus, a signal amplifier adapted to amplify a carrier wave modulated in frequency within a band of frequencies in accordance with an impressed signal, said amplifier being also effective to supply in its output substantial noise voltages modulated in amplitude at audio frequency, an amplitude limiter coupled to said amplifier, said limiter including an electron discharge device having an output circuit, a signal reproducer including a second electron discharge device having a control electrode coupled to said output circuit, amplitude modulation detection means also coupled to the output of said limiter for developing a negative bias potential upon said control electrode proportional to amplitude modulation of waves appearing in said output circuit, means for supplying to said control electrode a positive bias potential of selectable substantially constant value less than said negative potential as long as the amplitude of said carrier wave remains below a desired value, and means for preventing reversal of the net potential impressed upon said control electrode upon diminution of said negative bias potential.

12. In a radio receiving apparatus, a signal amplifier adapted to amplify a carrier wave modulated in frequency within a band of frequencies in accordance with an impressed signal, said amplifier being also effective to supply in its output substantial noise voltages modulated in amplitude at audio frequency, an amplitude limiter having an output circuit coupled to said amplifier, signal reproducing means including an electron discharge device having a control electrode coupled to said output circuit, amplitude detection means also coupled to said output circuit and arranged to apply to said control electrode a negative bias potential proportional to the degree of amplitude modulation of waves appearing in said output circuit, adjustable means for supplying to said control electrode from a point in said output circuit an opposing positive bias potential of selectable value thereby to provide a differential bias potential of such polarity as to tend to disable said electron discharge device, the magnitude of said differential potential in the absence of a carrier wave being normally sufficient completely to disable said electron discharge device and being selectable by said adjustable means to provide for reduction thereof to zero in the presence of a carrier wave of any desired value.

13. In a radio receiving apparatus, a signal amplifier adapted to amplify a carrier wave modulated in frequency within a band of frequencies in accordance with an impressed signal, said amplifier being also effective to supply in its output substantial noise voltages modulated in amplitude at audio frequency, an amplitude limiter coupled to said amplifier including an electron discharge device having an anode circuit, signal reproducing means including a second electron discharge device having a control electrode coupled to said anode circuit, amplitude detection means also coupled to said anode circuit for applying to said control electrode a negative bias potential proportional to

the degree of amplitude modulation of waves appearing in said anode circuit, and adjustable means coupled to the anode of said first electron discharge device for applying to said control electrode an opposing bias potential of selectable value thereby to provide a differential bias upon said control electrode tending to disable said electron discharge device, the magnitude of said differential potential in the absence of a carrier wave being normally sufficient completely to disable said electron discharge device and being selectable by said adjustable means to provide for reduction thereof to zero in the presence of a carrier wave of any desired value.

14. In a radio receiving apparatus, a signal amplifier adapted to amplify a carrier wave modulated in frequency within a band of frequencies in accordance with an impressed signal, said amplifier being also effective to supply in its output substantial noise voltages modulated in amplitude at audio frequency, signal reproducing means coupled to the output of said amplifier, means including an electron discharge device for amplifying and detecting amplitude modulated voltages appearing in the output of said amplifier, said means including means to reduce the gain of said electron discharge device only in the presence of a carrier wave, means for developing a potential proportional to said detected voltages, means for opposing said potential to provide a differential potential, and means responsive to said differential potential for at least partially disabling said signal reproducing means.

15. In a radio receiving apparatus, a signal amplifier adapted to amplify a carrier wave modulated in frequency within a band of frequencies in accordance with an impressed signal, said amplifier being also effective to supply in its output substantial noise voltages modulated in amplitude at audio frequency, signal reproducing means coupled to the output of said amplifier, means including an electron discharge device for amplifying and detecting audio frequency voltages appearing in the output of said amplifier, said means including means to reduce the gain of said electron discharge device in the presence of a carrier wave, said gain remaining substantially constant upon increase of said noise voltages, means for developing a potential proportional to said detected audio frequency voltages, selector means for opposing said potential to provide a differential potential, means responsive to said differential potential for at least partially disabling said signal reproducing means, and means associated with said signal reproducing means for preventing a reversal of said differential potential.

16. In a radio receiving apparatus, a signal amplifier adapted to amplify carrier waves modulated in frequency within a band of frequencies in accordance with an impressed signal, said amplifier being also effective to supply in its output substantial noise voltages modulated in amplitude at audio frequency, signal reproducing means coupled to said amplifier, means including an electron discharge device for amplifying and detecting audio frequency voltages appearing in the output of said amplifier, said means including means for reducing the gain of said electron discharge device in the presence of a carrier wave of predetermined amplitude, said gain remaining substantially unaffected by increase of said

noise voltages, means for developing a potential proportional to said detected audio frequency voltages, means rendering said last-named means nonresponsive to amplitude modulation of said detected audio frequency voltages, selector means for opposing said potential to provide a differential potential for at least partially disabling said signal reproducing means, and means associated with said signal reproducing means for preventing a reversal of said differential potential.

17. In a radio receiving apparatus, a signal amplifier adapted to amplify a carrier wave modulated in frequency within a band of frequencies in accordance with an impressed signal, said amplifier being also effective to supply in its output substantial noise voltages modulated in amplitude at audio frequency, signal reproducing means coupled to the output of said amplifier, means including an electron discharge device having a control electrode for amplifying and detecting audio frequency waves appearing in the output of said amplifier, the output of said amplifier being coupled to said control electrode through a circuit so proportioned that the output of said electron discharge device remains substantially constant with variations in intensity of said noise voltages, said circuit being arranged to reduce the gain of said electron discharge device in the presence of a carrier wave of predetermined intensity, means for developing a potential proportional to said detected audio frequency wave, selector means for opposing said potential to provide a differential potential, and means responsive to said differential potential for at least partially disabling said signal reproducing means.

18. In a radio receiving apparatus, a signal amplifier adapted to amplify a carrier wave modulated in frequency within a band of frequencies in accordance with an impressed signal, said amplifier being also effective to supply in its output substantial noise voltages modulated in amplitude at audio frequency, signal reproducing means coupled to said amplifier and including a first electron discharge device having a control electrode, means including a second electron discharge device having a control electrode for detecting and amplifying audio frequency waves appearing in the output of said amplifier, the control electrode of said second electron discharge device being coupled to the output of said amplifier in such a manner that the audio frequency output of said second electron discharge device remains substantially constant with variations in intensity of said noise voltages, rectifying means for applying to the control electrode of said first electron discharge device a negative bias potential proportional to said detected audio frequency wave, means for rendering said rectifying means nonresponsive to amplitude modulation of said detected audio frequency wave, selector means for applying to the control electrode of said first electron responsive device a positive bias potential less than said negative bias potential so long as the intensity of said carrier wave remains below a predetermined level, and unidirectional conducting means coupled to said first electron discharge device for preventing a reversal of the net bias potential applied to said first electron discharge device.
